CLAIM

The ornamental design for a console storage container, as shown and described.

DESCRIPTION

FIG. 1 is a front view of a console storage container showing my new design;

FIG. 2 is a front view thereof;

FIG. 3 is a rear view thereof;

FIG. 4 is a left side view thereof, the right side being a mirror image;

FIG. 5 is a top view thereof;

FIG. 6 is a top view thereof;

FIG. 7 is a bottom view thereof;

FIG. 8 is a perspective front view thereof; and,

FIG. 9 is a perspective front view thereof.

In the drawings, the broken lines depict portions of the article that form no part of the claimed design.
